UNITED STATES PATENT OFFICE.

JOEL UPHAM ADAMS, OF CINCINNATI, OHIO.

TRUSS.

Application filed December 28, 1921. Serial No. 525,530.

To all whom it may concern:

Be it known that I, JOEL UPHAM ADAMS, a citizen of the United States, residing at Cincinnati, in the county of Hamilton and 5 State of Ohio, have invented a new and useful Truss, of which the following is a specification.

This invention relates to truss pad constructions, the primary object of the invention being to provide means whereby unlimited movement of a pad may be had, with respect to its support, to insure against the pad slipping while in use.

Another object of the invention is to provide a pad which will be exceptionally soft, and one which will not irritate.

A still further object of the invention is to provide a pad having a roughened surface to eliminate any possibility of the pad slipping over the body of the wearer.

With the foregoing and other objects in view which will appear as the description proceeds, the invention resides in the combination and arrangement of parts and in 25 the details of construction hereinafter described and claimed, it being understood that changes in the precise embodiment of the invention herein disclosed, may be made within the scope of what is claimed, without departing from the spirit of the invention.

Referring to the drawings:

Figure 1 is a perspective view of a truss showing pads constructed in accordance with the present invention as applied thereto.

35 Figure 2 is a sectional view through a pad, and disclosing the means for compensating for movement between the truss proper and pad.

Figure 3 is a detail view of a pad and 40 connecting strap, and

Figure 4 is a plan view of the face of a pad, showing the roughened covering, or body engaging portion.

Figure 5 is a sectional view through the 45 pad as shown by Figure 4 of the drawings.

Referring to the drawings in detail, the reference character 4 designates a truss, to which the pads forming the subject matter of the invention are secured. The pad in its 50 preferred form embodies a plate 5 preferably circular in formation, which plate is formed with a central opening 6 designed to accommodate the head 7 formed at one end of the shank 8, the shank being provided 55 for securing the pad to the belt or support.

This plate 5 is preferably covered by a suitable fabric material indicated at 9. A rubber cover 10 is formed with spaced walls 11 and 12, the wall 11 or rear wall of the cover being secured to the plate, as by means of the screws 13 which pass through suitable openings in the rear wall and embed themselves in the threaded openings in the plate. The covering 10 is constructed to provide a container or pocket to accommodate the felt padding or other suitable material indicated at 14, the felt being held within the pocket and between the inner wall thereof and the plate to cushion the body engaging portion of the pad.

In order that the pad will be held against movement with respect to the body of the wearer, the outer surface of the pad is covered with a covering formed preferably of rubber and formed with a plurality of intersecting ribs 15, which ribs present roughened surfaces. A securing plate 16 clamps the rear wall 11 of the cover 10 to the plate 5, the screws 13 also passing through the plate 16 to accomplish this result, as clearly shown by Figure 2 of the drawing. The securing plate 16 is provided with a central opening, the walls thereof being curved to conform to the curvature of the head 7, whereby a ball and socket joint is provided between the pad and its support, to permit the pad to be moved to various positions, with respect to its support. The support may be of the usual construction, suitable means being provided to receive the shank 8 thereof, to secure the shank against movement and hold the same rigid.

By Figures 3 and 4 of the drawings, I have shown, that it is within the scope of the invention to provide pads of various shapes, and that the subject matter of the invention, may be applied to pads regardless of their shapes.

The connecting strap which connects the free ends of the truss is indicated at 17, and has one end thereof secured to a truss pad as at 18, the opposite end of the strap passing through a suitable buckle indicated at 19, whereby the length of the strap may be adjusted to meet the requirements of the user.

An extension 20 also has connection with the buckle 19 and is formed with an opening 21 to be positioned over the screw head 110

22 to secure the truss to the body of the wearer.

Having thus described the invention, what is claimed as new is:—

- 5 1. A pad comprising a plate, a cover for the plate, portions of the cover adapted to contact with the plate at the rear thereof, a securing plate contacting with a portion of the cover, means for securing the securing plate to the 10 first mentioned plate to clamp a portion of the cover therebetween, a shank having a head, said head adapted to be clamped between the plates, and a cushioning element disposed under the cover.
- 15 2. A pad comprising a plate, said plate

having a central opening, a securing plate having a central opening and having the walls thereof curved, a head positioned between the plates and adapted to contact with the curved walls of the opening of the securing plate to provide a ball and socket joint, a cover, and a cushioning element disposed under the cover.

In testimony that I claim the foregoing as my own, I have hereto affixed my signature in the presence of two witnesses,

JOEL UPHAM ADAMS.

Witnesses:

RITA SCHEHL,
AIDA STEPHENSON.
